MITE BOX

Lloyd J. Ten Pas, Cedar Grove, Wis.

Application January 7, 1955, Serial No. 33,895

Term of patent 14 years

(Cl. D34—11)

The figure is a perspective view of a mite box embodying my new design taken from a point above, at one side and to the rear and showing its face.

The opposite face, not shown, has substantially the same appearance as the face shown in the drawing.

The legible matter shown in broken lines is for illustrative purposes only.

I claim:

The ornamental design for a mite box, as shown and described.
